UNITED STATES PATENT OFFICE.

MAX GONICK, OF NEW YORK, N. Y.

SAFETY COLLAR-BUTTON.

1,268,342.

Specification of Letters Patent.

Patented June 4, 1918.

Application filed September 10, 1917. Serial No. 190,617.

To all whom it may concern:

Be it known that I, MAX GONICK, a citizen of the Republic of Russia, and a resident of New York, borough of Bronx, county of Bronx, and State of New York, have invented a certain new and useful Improvement in Safety Collar-Buttons, of which the following is a full, clear, and exact specification.

10 This invention relates more particularly to a form of button which is an improvement on the collar button disclosed in my Patent No. 1,206,529, dated November 28, 1916, and has for its object primarily to 15 provide a device whereby collars and cuffs may be detachably fastened on shirts, waists and like garments besides being adapted for attaching together other parts of garments. The invention consists essentially of a rigid 20 post with a base plate on one of its ends, and having a head on its other end. Lengthwise of the post is a groove which terminates with a notch formed in the post in spaced proximity to the base plate. Arranged in the groove crosswise of the notch 25 is a rod, or finger of spring metal having one end fixed to the post at the base plate so that the other part of the rod may be sprung outwardly and inwardly of the 30 groove, and movably mounted in the notch between the rod and the post is a clamp, or holding element which serves a purpose similar to the one disclosed in said patent.

A further object of the invention is to 35 provide a safety button of a simple and efficient construction which is susceptible of being made in various sizes and shapes.

A practical embodiment of the invention 40 is represented in the accompanying drawing forming a part of this specification in which similar characters of reference indicate corresponding parts in all the views, the said invention being more fully described hereinafter, and then pointed out in 45 the claims at the end of the description.

In the drawing, Figure 1 is a fragmentary view of the upper part of a garment showing one form of my improved collar button applied thereto.

50 Fig. 2 is an elevation of the button showing an edge view of the clamp of the button.

Fig. 3 is an elevation of the button showing an end view of the clamp.

55 Fig. 4 is an enlarged detail sectional view taken on the line IV-IV of Fig. 3, and

Fig. 5 is a detail sectional view taken on the line V-V of Fig. 4.

The collar button has a post 10 with a head 11 on its upper end and a base plate 60 65 12 on its lower end, all of which may be of any desired shapes and sizes. The post 10 may be of solid metal with the head and base-plate being integrally formed thereon, or the post may be made of sheet metal with 65 the head and base-plate attached thereto in any suitable manner.

The post 10 is grooved lengthwise, as at 13, so that the groove preferably extends from the juncture of the head 11 to a part 70 of the post in spaced proximity to the base plate 12, and the lower end of the groove terminates with a notch, or recess, as 14, which may be somewhat of a cone shape, as shown, as well as being of a depth somewhat 75 deeper than the groove 13.

Disposed in the groove 13 crosswise of the notch 14 is a rod, or finger 15 which is made of spring metal, or other yielding material, and one end of this spring rod is 80 fixed, at 16, to the lower end of the post. This rod is of a length so that its second end extends in close movable proximity to the underside of the head of the post, besides being slightly countersunk in the groove. 85 By this arrangement the upper part of the rod 15 may be sprung outwardly and inwardly of the groove 13 of the post.

Movably mounted in the notch 14 of the post 10 is a clamp, or holding element 17 90 which serves a purpose similar to the clamp employed in my Patent No. 1,206,529, dated November 28, 1916. The clamp may be of any suitable type, though this clamp is preferably formed with two spaced straight arms 95 18 and 19 with a loop, as 20, formed on one of the corresponding ends thereof, while the second ends of these arms are bridged by a crossbar 21. The crossbar 21 is substantially rectangular, as well as being of a length 100 slightly longer than the width of the post 10 of the button, and this cross bar is seated in the apex of the notch 14 between the post and the spring rod 15 so as to be yieldingly clamped therein. The clamp 17 is of a 105 length and also of a size to permit of being guided back and forth from a position extending laterally from the post in spaced relation to the base plate to a position in straddle arrangement over the post 10 and over 110 the head 11, the spring action of the rod 15 serving to releasably hold the clamp in a

desired position. When the clamp is disposed over the post and head the button may be employed by guiding the post with the clamp through a buttonhole of a garment, 5 and the clamp is then sprung in lapping arrangement on the face of the garment opposite to that in contact with the base plate of the button. The head and post of the button are then guided in the usual fashion 10 through a second buttonhole provided in the garment to register with the other button-hole.

In the foregoing description, I have embodied the preferred form of my invention, 15 but I do not wish to be understood as limiting myself thereto, as I am aware that modifications may be made therein without departing from the principle, or sacrificing any of the advantages of this invention, 20 therefore I reserve to myself the right to make such changes as fairly fall within the scope thereof.

Having thus described my invention, I claim as new and desire to secure by Letters 25 Patent:—

1. In a collar button, a rigid post with a base plate and a head on its ends, and a spring actuated finger projecting alongside of the post from the base plate so as to be

sprung back and forth from the post whereby a clamp may be operatively mounted on the post, substantially as set forth. 30

2. In a collar button, a rigid post with a base plate and a head on its ends, said post having a groove lengthwise thereof, and a 35 rod of spring metal having one end held to the post at one end of the groove so as to be sprung outwardly and inwardly of the groove, the said rod being adapted to operatively retain a clamp on the post, substantially as set forth. 40

3. In a collar button, a rigid post with a base plate and a head on its ends, said post having a groove lengthwise thereof and having a notch at one end of the groove, and a 45 rod of spring metal disposed in the groove crosswise of the notch as well as having one end held to the post for being sprung inwardly and outwardly of the groove whereby a clamp may be operatively retained on the post, substantially as set forth. 50

This specification signed and witnessed this 8th day of September A. D. 1917.

MAX GONICK.
